UNITED STATES PATENT OFFICE

134,857

DESIGN FOR A GYRO-TOP OR SIMILAR TOY

Motiejus Buzas, Chicago, Ill.

Application March 12, 1942, Serial No. 106,173

Term of patent 14 years

To all whom it may concern:

Be it known that I, Motiejus Buzas, a citizen of the United States of America, residing at Chicago, county of Cook, and State of Illinois, have invented a new, original, and ornamental Design for a Gyro-Top or Similar Toy, of which the following is a specification, reference being had to the accompanying drawing, forming a part thereof, wherein:

Figure 1 is a front view of a gyro-top or similar toy, showing my new design.

Figure 2 is a side view.

Figure 3 is a top plan view.

I claim:

The ornamental design for a gyro-top or similar toy, as shown.

MOTIEJUS BUZAS.
